UNITED STATES PATENT OFFICE.

MAX M. GETO, OF BROOKLYN, NEW YORK, ASSIGNOR TO WATCH PROTECTOR CORPORATION, OF NEW YORK, N. Y., A CORPORATION OF NEW YORK.

WATCH PROTECTOR.

Application filed August 9, 1921. Serial No. 490,931.

To all whom it may concern:

Be it known that I, MAX M. GETO, a citizen of the United States, and a resident of the city of New York, borough of Brooklyn, in the county of Kings and State of New York, have invented a new and Improved Watch Protector, of which the following is a full, clear, and exact description.

This invention relates to a watch protector, and has for an object the provision of a simple, efficient, economically manufactured device whereby the improper removal of a watch from a person's pocket is made impossible without the owner of the watch being made aware of this attempt.

Another object resides in the provision of means whereby the slightest attempt to remove the watch will instantly cause the engagement of the protector with the pocket, whereby the watch cannot be removed therefrom.

A further object resides in the provision of means which acts to achieve the above-mentioned objects and which, at the same time, excepting when operated in a particular way, appears merely to be a neat and artistic ornament or charm used in connection with the watch and chain.

A still further object resides in the particular construction and arrangement of parts which are hereinafter described and claimed and shown in the accompanying drawings.

The invention is illustrated in the drawings, of which—

Figure 1 is a vertical transverse section taken through a pocket showing the watch and the protector in the pocket with the protector in the inoperative position;

Figure 2 is a similar section showing the protector in the operating position;

Figure 3 is an enlarged vertical section taken through the protector when the parts are in their normal position;

Figure 4 is a similar section showing the parts in their operative position; and

Figure 5 is a horizontal section taken on the line 5—5 of Figure 4.

This invention, as shown in the drawings, which indicate the preferred form, is adapted to be used for the protection of a watch, such as 1, when it is inserted within a watch pocket 2 which has walls, such as 3 and 4, lying closely adjacent the watch. The watch is provided with the usual pivoted ring 5 to which a small link 6 is con-

nected. This link is adapted to extend into the lower end of a casing 7 and to embrace a bar 8 thereof, whereby the casing is connected at its lower end to the watch 1. This casing 7 may be of any suitable material and is shown shaped somewhat cylindrical and to some extent simulating an acorn. This casing is hollow and the upper edges thereof are flared out as at 9. A cap 10 of any suitable material is provided with an outwardly projecting flange portion 11 which can be spun over the upper edge of the casing 7. This cap is provided with a central aperture 12 through which a pin or stub shaft 13 extends. This shaft at its upper end is provided with an aperture 14 through which a link 15 of a watch chain 17 extends. This stub shaft or pin 13, at its lower end, is provided with an outwardly extending flange portion 18 between which and the inner face of the cap 10 a coil spring 19 is disposed, which spring tends normally to hold the shaft 13 well within the casing 7, as indicated in Fig. 3.

Disposed in the cap 10, and preferably at intervals around the periphery thereof, are a plurality of apertures 20. Through these apertures a plurality of sharp-pointed spears or garment-engaging means 21 are adapted to extend, as shown in Fig. 4. The lower ends of these spears 21 are each curved to lie in a slot 22 in the lower end of the stub shaft 13 and to be loosely restrained therein by a coiled ring 23.

The spring 19 extends from the inner face of the cap 10 and along the stub shaft 13. The lower end of the spring bears against portions of the spears 21 and thereby tends to force them outwardly at all times. The upturned lip portions 24 on the bottom of the casing oppose the action of the spring when the stub shaft is in the normal position.

However, when an attempt is made to pull or move the chain 17 with respect to the watch 1, the stub shaft 13 is moved. The movement of the stub shaft causes the spears 21 to be pulled out of the cap 10 through the apertures 20, and when they are pulled out they extend upwardly from the protector casing and almost immediately engage either one of the walls of the pocket in which the watch is closely confined. It is to be observed that any suitable number of spears may be provided and can be connected to

the common stub shaft 13. It is also to be noticed that when in normal position the parts are contained within the casing and that the protector simulates in appearance 5 a charm or other artistic device. This protector casing may be made in any desired shape to suit the tastes of the person buying it. In order to properly withdraw the watch from the pocket, the casing 7 should be 10 grasped in the hand, and not the watch chain 17. If this is done, there is no relative movement of the chain with respect to the casing which would cause the spears to be pulled out to engage with the garment fabric. 15 It will be observed, therefore, that I have provided a simple, efficient, economically manufactured device whereby it is absolutely impossible to successfully withdraw a watch from a pocket by pulling on the ordinary 20 watch chain, but that in order to get the watch out the hands or fingers must be inserted within the pocket to grip the protector casing. In substantially all cases, if this were done by an improper person the 25 attention of the person owning the watch would be attracted.

What I claim is:

1. A watch protector which includes a casing having a cover with apertures therein, a 30 stub shaft slidable in said casing, a spring within the casing engaging the stub shaft, said spring being expandible to hold the stub shaft retracted within the casing, the lower end of the stub shaft being provided with a 35 plurality of longitudinal slots, a flange on

the end of the stub shaft, a plurality of spears located in said slots, and a flexible ring surrounding the end of the stub shaft and the ends of the spears to hold them in 40 said slots.

2. A watch protector which includes a casing having a cover with apertures therein, a stub shaft slidable in said casing, an expandible spring within said casing and engaging with the stub shaft to hold it retracted therewithin, the lower end of the stub shaft being provided with a plurality of longitudinal slots, a flange on the end of the stub shaft, a plurality of spears located 45 in said slots, and a flexible ring surrounding the end of the stub shaft and the ends of the spears to hold them in the slots, said spring being disposed around the shaft between the cover and bearing at one end 50 against the spears and tending to move the spears away from the stub shaft.

3. A watch protector which includes a casing having a cover with apertures therein, a 60 slidable stub shaft extending into said casing and having a slotted flanged head on the lower end thereof, a plurality of spears disposed in said slots and pivotally connected to the stub shaft, and an expandible spring disposed around the stub shaft, one end of the spring bearing against the cover and the other end of the spring bearing against the 65 spears and tending to force them outward away from the stub shaft.

MAX M. GETO.
